COMBINED HASSOCK AND CHAIR

Edgar N. Genovese, Baltimore, Md.

Application March 30, 1951, Serial No. 218,432

5 Claims. (Cl. 155—152)

1

This invention relates to household furniture and more particularly to a combination hassock and chair unit.

The invention has for an object the provision of a new and improved hassock that can be used as a chair.

Another object of the invention is to provide a new and improved hassock structure that can be operably varied in appearance to form a chair when opened and when closed it forms into a compact hassock when desired.

Other objects of the invention can be appreciated as it is outlined in detail.

For a better understanding of the invention and the objects thereof reference is made to the accompanying drawings, wherein a particular form is indicated by way of example. These drawings in conjunction with the following description show a preferred construction while the claims emphasize the scope of the invention.

In the drawings:

Figure 1 is a front perspective view of a combination hassock and chair unit embodying this invention, shown in closed position;

Figure 2 is a similar view to that shown in Figure 1, with the unit opened or unfolded into the chair position;

Figure 3 is a sectional elevation taken on line 3—3 of Figure 1;

Figure 4 is a front sectional elevation of the unit taken on line 4—4 of Figure 2;

Figure 5 is a detail indicating the type of hinge used in this embodiment;

Figure 6 is a modified form of the hassock in perspective and shown in closed position;

Figure 7 is a similar view with the hassock in closed position;

Figure 8 is a sectional view on line 8—8 of Figure 7; and

Figure 9 is a sectional view on line 9—9 of Figure 6.

Similar parts in the drawings are designated by the same reference numerals.

The drawings show a hassock unit 10 of conventional contour and a structure of hollow box-like framed form exteriorly cushioned. However, in its construction it has a recess 11 in its middle portion formed into a depression in its upper section encompassed by a seat 12, and side walls 13. A rotatable body member 14 of suitable box-like form is pivoted or hinged on pins 15 passing transversely from the walls 13 and positioned so as to permit this body 14 being rotatably placed angularly to form a back, which the user can rest his back against while sitting on the

2

seat 12. The member 14 is arbitrarily termed a back, and when folded down on the seat 12 into the recess 11 closes the unit into a hassock on the top surface of which the user can sit, put his feet on, or otherwise use it in the conventional hassock manner. When so folded down the back 14 is secured by a strap 16 rotatably attached to the lower section 18 of the hassock by a rivet 30 and is preferably arranged with a snap or button fastener 17 that engages with part 31 which is attached to the edge of seat and back 14 of the hassock. The back 14 is exteriorly contoured to conform with the hassock surfaces it aligns with.

The cushions of the hassock are filled with material of resilient or partly resilient nature in the usual manner, with a leather or strong fabric covering forming a cushioning surface on its exterior. The device is simple in construction, effective in its use, and can be manipulated in a facile manner. When the back 14 is raised, its lower portion fits in a spacing 20 in the seat adjacent to the rear, so it will be braced and held up rigidly enough against the surface 39 to sustain the body of the user pressing against it. This is clearly shown in Figures 4 and 8. The hassock used as a chair when the back 14 is up, is especially suitable for television viewing.

It will be noted that the elongated slot 19 used in this form enables the back 14 to be adjusted forwardly and backwardly. The back is pulled forward from its horizontal position to the extent of travel allowed by the length of the elongated slot. Then it is rotated backwardly on the pins 15. This brings the back over the spacing 20 so it may be slid therein, and tilts the back to form the contour of a chair with the seat. The purpose of this is to have the rear wall 21 extend up the proximate height of the seat level and present a closed in appearance when closed in for use as a hassock. At the same time it makes the back easier to manipulate in a limited space and particularly when a portion of it is inserted in the spacing 20. When used as a hassock the back rests on the seat 12 and top edge of wall 21.

In the modified form shown in Figures 6, 7, 8 and 9, the structure is made with its pins 15 inserted through round holes in the back, avoiding the use of the elongated slots previously included. This enables the back to swing up as on a hinge without adjustability to the back in a forward and backward direction, as previously shown. The spacing at 20 is left without a wall in back to enclose the lower portion of the back when open, but does need a false bottom partition 22 to reinforce the rear structure of the hassock as

shown. This construction leaves the rear surface of the back free of any restraint.

While but two general forms of the invention are shown herein, it is not intended to limit this application to such specific forms as it is appreciated that other structures could be made, that would use the same principles and come within the scope of the appended claims.

Having thus described the invention, what is claimed is:

1. A hassock unit comprising a body having its upper section depressed into a substantially U-shaped recess for a user to sit on and form a chair and having its seat surface at the bottom with walls at the sides, and a movable back hinged to said body, said back being arranged to fold into said recess and fill it completely so that a hassock of uniform outer contour will be formed thereby, means for securing the back to said body, bracing means for the back to hold it upright when it is opened up to form the hassock into a chair, said seat surface being angularly arranged with respect to the under surface of the body so as to add to the comfort of the user sitting on said seat, said body and back being of hollow box-like construction with cushions externally attached thereto.

2. A seat unit comprising a seat, an upright arm rest on each side of said seat projecting above the upper surface of said seat, whereby said seat and said arm rests form a substantially U-shaped recess as viewed from the front of said unit, said seat having a downward extension at its end and intermediate the rear ends of said arm rests, a pivotal member positioned between the side arms and adjacent said downward extension, pivot

means at each side of said member and connected to each of said arm rests, said member, when in an upright position, abutting said rear extension to brace said member so as to form a back rest and said member when pivoted to a horizontal position resting upon said seat to form a hassock, the tops of said arms and said member, when in said horizontal position, all being of the same contour to form a continuous seating surface.

10 3. A seat unit as set forth in claim 2, wherein the pivot means consist of oppositely disposed pins secured to vertical walls of the arm rests and extending through slots provided in said member.

15 4. A seat unit as set forth in claim 2, wherein the pivot means consists of a pin carried by vertical walls of the arm rests and extending through said member.

5. A seat unit as set forth in claim 2, including 20 a strap secured to the hassock and detachably securable to said member.
